J. J. ZOFSAK.
CHILD'S COT FOR VEHICLES.
APPLICATION FILED SEPT. 20, 1916.

1,265,157.

Patented May 7, 1918.

JOHN J. ZOFSAK,
INVENTOR.

BY *William A. Kirtle*
ATTORNEY.

UNITED STATES PATENT OFFICE.

JOHN J. ZOFSAK, OF GREENSBURG, PENNSYLVANIA.

CHILD'S COT FOR VEHICLES.

1,265,157.

Specification of Letters Patent.

Patented May 7, 1918.

Application filed September 20, 1916. Serial No. 121,164.

To all whom it may concern:

Be it known that I, JOHN J. ZOFSAK, a subject of the Emperor of Austria-Hungary, residing at Greensburg, in the county of Westmoreland and State of Pennsylvania, have invented certain new and useful Improvements in Children's Cots for Vehicles, of which the following is a specification.

The present invention relates to cots for children adapted to be used in vehicles and more particularly in connection with automobiles, and has for its object the provision of a cot whereby the child may be laid in a recumbent position and remain secure against dislodgment in the course of travel of the automobile. Means is also provided to protect the occupant of the cot from the inclemency of the weather, and for attachment to any suitable part of the automobile such as the back part of the front seat in an ordinary "touring car".

Provision is also made for observing the child by its guardian without rising from the latter's position in the rear seat of the automobile.

The cot may be detached and removed bodily from the vehicle and used as an ordinary cot in the household, being also provided with means for the child's comfort.

All of the above features will be more fully explained and set forth in this specification hereinafter.

In the accompanying drawing forming part of this specification, I have shown one complete example of the physical embodiment of my invention constructed according to the best mode I have so far devised for the practical application of the principles of my invention.

Figure 1 is a plan view of my invention.

Fig. 2 is a central longitudinal section of the device taken on line 1—1 of Fig. 1.

Fig. 3 is a vertical cross-sectional view taken on line 2—2 of Fig. 1.

Fig. 4 is a plan view of a cover or shield used in connection with my invention.

Fig. 5 is a diagrammatic view illustrating a special feature of the invention.

The numerals 1 and 2 indicate two side pieces which are made preferably of wood or other light weight material, and together form the rear support of the cot, 3 and 4 being similar companion pieces forming the

support for the front side of the cot. 5, 6, 7 are cross-bars between the sides 8, 9 of the cot, and located longitudinally upon 5 and 7 are the slats 10, 11, 12, 13, 14 which in turn carry a mattress 15. It will be observed the mattress 15 may be removed bodily along lines 16, 17, 18, 19 from the cot 60 for cleaning and airing purposes.

Extending across the ends of the cot are two cross-pieces 20, 21 and fastened to these and the cross-bars 5 and 7 are longitudinal slats 22, 23, etc., which form supports for the 65 upholstery 24, 25. "Front" and "back" boards 26, 27 respectively are attached to the side pieces 1, 2, and 3, 4 to form a suitable support for the upholstery 28, 29. A "cut out" or depressed portion 30 is made in the 70 upholstered portion 25 to receive a removable soft pillow 31. A mirror 32 is located in the "back" upholstered portion 29 for a purpose set forth below. Hooks 33, 34 are provided as shown adapted to engage complementary "eyes" or hooks on the rear portion of the front seat of the vehicle (not shown).

Two "shoes" 35, 36 having thereon castings 37, 38 designed to receive the ends of 80 the side pieces, 1, 2, 3, 4, and with rollers 64, 65, etc., form the base of the cot. The rollers or casters are for use in the household when the cot is used as an ordinary house bed. The castings 37, 38, etc., being bolted 85 to the shoes 35, 36 as seen in the drawing, it is evident that the ends of the side pieces 1, 2, 3, 4 and the shoes are securely and firmly held together at all times.

The ends of the cot are covered with cloth 90 from a point at 39 to 40, thus covering the structural portions of the cot. The rear and front of the side walls 8, 9 are likewise covered from 44 to 45, and 46 to 47 respectively for the same purpose.

Straps 48, 49 preferably of leather are attached to the rear wall 8, and engage over buttons 50, 51 on the front face 9 of the cot to assist in holding the child against dislodgment due to the jolting of the vehicle in 100 the course of travel.

For use in inclement weather a cover 58 of water proof material of shape shown in Fig. 4 is provided having button holes 52, 53, etc., on the edges of same for engagement with 105 complementary buttons 54, 55, etc., on the

sides and ends of the cot as is readily understood. Ventilating openings are provided at 56, 57, etc., in the cover. A "flap" door 59 is made in the cover 58 with a tongue 60, which can be fastened back upon itself to a button at 61, thus admitting light to the child under the cover when desired. Directly under the "flap" 59 is a celluloid or other transparent shield 62 to admit light but at the same time give protection against the elements.

The use of the mirror 32 to observe the movements or condition of the child occupying the cot is illustrated diagrammatically in Fig. 5. 63 indicates the position of the guardian of the child when the former occupies the rear seat of a vehicle such as an automobile, the cot being attached to the rear of the front seat as shown. The line of vision passes from the eye as shown by the dotted lines through the transparent shield 62 when uncovered, and to the mirror 32 which displays any movements of the child, thus the guardian need not leave his or her seat to observe the occupant of the cot.

From the foregoing description it is believed a clear idea of the uses and purposes of the cot and its adaptability to out-door

and indoor use may be obtained without further elaboration.

What I claim is:—

1. In a child's cot front and rear side walls of different heights having oppositely disposed lower extremities forming feet, a pair of longitudinally disposed shoes having upturned ends, castings mounted on the shoes adapted to engage the feet of the side walls, means for connecting the side walls together, and reflecting means mounted in the higher side wall for observing the occupant of the cot.

2. In a child's cot front and rear side walls of varying heights supporting and connecting means between the said walls, a mirror angularly arranged in the higher wall, protective covering means for the child carried by the side walls, and a hinged flap-door and transparent window in said protective means for observing the occupant of the cot therethrough.

In testimony whereof I affix my signature in the presence of two witnesses.

JOHN J. ZOFSAK.

Witnesses:

JOHN F. SWEENEY,
ANNA O'DONNELL.
